UNITED STATES PATENT OFFICE.

FRIEDRICH ROEMER, OF STUTTGART, GERMANY.

FIRE-EXTINGUISHER.

No. 866,888.

Specification of Letters Patent.

Patented Sept. 24, 1907.

Application filed October 19, 1905. Serial No. 283,660.

To all whom it may concern:

Be it known that I, FRIEDRICH ROEMER, of Remscheid, a citizen of the German Empire, residing at Stuttgart, in the Kingdom of Würtemberg, Germany, have invented certain new and useful Improvements in Fire-Extinguishers, of which the following is a description, reference being had to the accompanying drawing, and to the letters and figures of reference marked thereon.

10 In gas generating fire extinguishers hitherto known the generation of the gas pressure required to deliver a stream of water was produced by previously mixing the water stored in the receptacle with chemicals and suddenly emptying into this chemical mixture a quantity of acid stored in glass tubes until wanted.

The fire extinguisher which constitutes the present invention is distinguished from such prior extinguishers in that its charge consists only of an easily handled cylindrically shaped cartridge which is supplied to the extinguisher in the desired number and no chemicals are mixed with the stored water.

Since the time consuming operation of mixing the chemicals as well as the introduction of breakable glass tubes in complicated holding devices, etc., is entirely done away with, my improved extinguishers are charged without trouble and delay upon the outbreak of a fire, rapidly and as often as desired, simply by the introduction of the easily handled cartridges into the receptacles containing the water.

30 The novel features of my invention reside in the rendering unnecessary of all chemicals, in concentrated form required for the generation of the gas, in the stored water, as well as in the construction of an easily handled cylindrical chemical cartridge, which, divided into two compartments, contains in concentrated form all the chemicals required for the generation of the gas.

The invention is illustrated in the accompanying drawings, in which,—

40 Figure 1 is a sectional elevation through a fire extinguisher, embodying my improvements. Fig. 2 is a sectional detail view of one form of cartridge containing receptacles with the cartridges therein. Fig. 3 is a similar view of another form. Fig. 4 is a horizontal section through the form shown in Fig. 2. Fig. 5 is a similar section through the form shown in Fig. 3.

The cartridge consists of a perforated metal shell *f* and comprises the chemical compartments *a* and *b*, *a'* and *b'*, or *a²* and *b²*.

50 To discharge the apparatus the compartments are

either opened by the forcing downward of the hammer *d*, Fig. 1, as far as the downwardly directed outlets *o o*, Fig. 1, or *o' o'* Fig. 2, by means of the pin *m* Fig. 1, or of the cones *i i* Fig. 2, in which latter case the compartments are completely destroyed, Fig. 2. 55

In order that the concentrated chemicals may be diluted with water before they come in contact with each other when the cartridges are discharged there is arranged between the compartments *a* and *b*, *a'* and *b'* or *a²* and *b²*, a separating wall *k*, so that the chemicals cannot mutually contact directly but only in a round-about way through the water contained in the receptacle whereby they are diluted. The separate wall is made of lead or of similar material. With cartridges, which are discharged, as in Fig. 2, by opening the outlets *o' o'*, the dilution of the concentrated chemicals is caused by the fact that the outlets are arranged as far as possible apart from each other and eccentrically to the center of the compartments *a'* and *b'*, so that there exists an intermediate 70 space *x*, Fig. 2, filled with water. Since the concentrated chemicals must pass this intermediate space before they can mutually contact they are, therefore, also diluted with water.

The cover *h* is loosely placed in the shell *f* and is 75 driven down with the hammer *d* when the latter is driven down. *g*, Fig. 1, represents a yoke, which is secured to the receptacle *e* Fig. 1, and serves to receive the cartridges. Figs. 4 and 5 represent in cross section the cartridges of Figs. 1, 2 and 3. 80

Having thus described my invention what I claim and desire to secure by Letters Patent of the United States is—

1. A fire extinguisher comprising a water containing tank having a suitable nozzle, a cylindrical container carried in the upper part of said tank and having openings leading to the tank, a partition dividing said tank into two compartments, hermetically closed cartridges containing different chemicals which when mixed together in the presence of water generate gas to expel the water, one of said cartridges being located in each compartment, whereby the said cartridges are separated by the partition, and means for opening the cartridges at their lower ends to permit the contents to be projected and commingled below the partition, substantially as described. 85 90 95

2. A fire extinguisher comprising a water tank having a delivery nozzle and a cylindrical cage or container having a perforated exterior wall, and an imperforate interior wall dividing the cage into two compartments, a hermetically closed cartridge located in each compartment, said cartridges containing different chemicals which when combined in the presence of water generate gas to expel the water, and means for opening the cartridges 100

at their lower ends whereby the contents is permitted to fall down and commingle below the imperforate partitions, substantially as described.

3. A fire extinguisher comprising a water tank having
5 a delivery nozzle, a cylindrical container located in the upper part thereof and having a perforated outer wall, a vertically disposed imperforate partition in said container located to one side of the center thereof and dividing the same into two compartments of unequal size,
10 a cartridge fitting in each compartment, and means for

opening the cartridges at the lower ends to permit the discharge of material contained therein, substantially as described.

In testimony whereof I have hereunto affixed my signature, in presence of two witnesses.

FRIEDRICH ROEMER.
